UNITED STATES PATENT OFFICE.

OSCAR A. BERMAN, OF CINCINNATI, OHIO.

SOUND TRANSMISSION.

Application filed October 30, 1922. Serial No. 597,981.

To all whom it may concern:

Be it known that I, OSCAR A. BERMAN, a citizen of the United States, and residing at 224 East 8th Street, Cincinnati, State of Ohio, have invented certain new useful Improvements in Sound Transmissions, of which the following is a specification.

This invention relates to improvements in a device for enhancing the sound effect of sound transmission and particularly of radio transmission.

It is an object of the invention to amplify and clarify the sounds transmitted by radio, or in some other way, through the utilization of strings of an instrument which are caused to swing in accordance with the sound vibrations produced by the receiver and to introduce into the sounds produced in this manner those overtones and other tones which frequently are lost in the transmission of sound.

It is also an object of the invention to set up the auxiliary vibrations of the strings of a stringed instrument by utilizing a sound box in connection with the receiver and by detachably connecting this sound box with a stringed instrument in such manner that a mutual influence through said sound box is produced, the sound vibrations of the receiver causing through said sound box the strings of the instrument to swing and the vibrations of the strings tending to clarify the sound vibrations of the receiver.

It is furthermore an object of the invention to provide a device of this kind in which receiving instruments of various forms may be used and to render the device adaptable for attachment of an ordinary head receiver or those receiving instruments which are now in use with magnifying devices and the like.

It is also an object of the invention to provide in a device of this character means by which the influence of the strings of the instrument upon the transmission of sound may be varied in accordance with the regulation of these vibrations which ordinarily is applied to stringed instruments.

With these and numerous other objects in view, an embodiment of the invention is shown in the accompanying drawing and is described in the following specification.

In the drawing:

Fig. 1 is a top plan view of a piano with parts shown broken away and to which the device has been attached;

Fig. 2 is a perspective view of the sound box itself with a receiving mechanism connected therewith;

Fig. 3 is a sectional view through the sound box, the receiving device being shown in elevation, and

Fig. 4 is a fragmentary detail view in elevation of a modified form.

The device comprises principally a sound box which may be constructed as a tubular member 1 of whole or circular, or square cross-section; as desired, this tubular member being provided with a longitudinal slot 2, which preferably extends from one edge 70 to the other of the box. The ends of the box preferably are left open.

The means for fastening the sound box to a stringed instrument comprises in the preferred form, stems 3 which are secured to the wall of the box near the end thereof and in opposition to the slot 2. The stems extend through the slot and terminate in hooks which may partly embrace the strings of an instrument. For the purpose of clamping the device to the selected strings or to the frame if desired, the projecting end 5 of each stem is threaded and carries a nut 6 through which the stem may be shifted axially upon rotation of the nut. A washer 7 in cooperation with the terminal hook of the stem will then act as a clamping member for securely holding the device in place directly above a plurality of strings of the instrument, the strings between the stems 30 being however sufficiently remote from the sound box so as not to be interfered with in their vibrations.

The stringed instrument with which in the described embodiment the device is shown combined is shown here as a piano 10 having a frame 11 with the strings tensioned across said frame in the well known arrangement. The strings 12 are illustrated diagrammatically only and are shown in a number smaller than the number with which these strings are usually used. While those strings to which the sound box is attached are naturally prevented from vibrating in accordance with the sounds emanating from the box, it is to be noted that in the modern piano a plurality of strings of the same tone value are usually used and that therefore even in spite of the clamping effect exerted on two of the strings of the piano 110 the mutual influence between strings and sound box will extend to strings of that tone

value to which the clamping elements are fastened.

The sound box is combined with a receptacle or socket 20 into which some electromagnetic device 21 may be inserted or to which said electromagnetic device may be secured in any suitable way. This electromagnetic device, which serves for converting the fluctuations in current in each sound 10 vibration, may have any desired construction and may, for instance, be the receiver which in radio transmission is frequently combined with the magnifier or amplifier. The current is introduced through the wires 15 22 and a clamping screw 24 serves for maintaining the sound transmission device in a suitable position with respect to the sound box 1.

In Fig. 4 this socket for receiving the device converting the electrical vibrations into sound vibrations is shown as the ordinary head receiver including the two ear pieces 30 which are secured by clamping screws 31 to a head band 32. These ear pieces are inserted into the branches 33 of a socket 34 which is in communication with the interior of the sound box 1.

Upon the transmission of sound signals, and especially of musical tones, as for instance by radio, the sound vibrations produced in the electromagnetic devices shown will be amplified through the attachment of the sound producing device with the sound box. These amplified vibrations will set up 35 harmonic vibrations within the strings which are in proximity to the sound box, and these harmonic vibrations will combine with the sound vibrations produced in the electromagnetic device to amplify and clarify the tones produced. Many of the overtones 40 which ordinarily are not received by the human ear if produced in the electromagnetic device will influence the strings of the instrument to cause them to vibrate and will 45 thereby set up sound vibrations within the sound box which otherwise would not be produced therein.

I claim:

1. In combination with a stringed instrument having a sound box, a second sound box, an electromagnetic sound reproducing device associated with the second sound box and means for securing said second sound box to the stringed instrument.
2. In combination with a stringed instrument having a sound box, a second sound box, a radio receiving device associated with the second sound box and means for clamping said second sound box to spaced strings 60 of the stringed instrument.
3. In combination with a stringed instrument, having a sound box, a second sound

box having an opening therein, a radio receiving device associated with the second sound box, and means for securing said second sound box to the stringed instrument with the opening of said box in opposition to the strings.

4. In a device of the character described, the combination of a tubular sound box having a radially projecting socket and a longitudinal slot in opposition to said socket, an electromagnetic radio receiving and sound producing device detachably mounted in said socket, and means extending through the slot of the sound box for fastening the sound box to a stringed instrument.

5. In combination with a stringed instrument having a sound box, a second sound box spaced at a slight elevation from the strings, and a radio receiving and sound producing device connected with said second sound box.

6. In combination with a stringed instrument having a sound box, a second sound box having an opening, means for spacing said second sound box from the strings of said instrument with the opening directed toward said strings, and a radio receiving and sound producing device connected with 90 said second sound box.

7. In combination with a radio receiving and sound producing device and a stringed instrument having a sound box, a second sound box interposed between said radio receiving device and the stringed instrument.

8. In a device of the character described, the combination of a sound box, a radio head receiver having two ear pieces, and means for establishing communication between said ear pieces and the interior of the sound box.

9. In combination with a piano having a frame for strings, a tubular sound box provided with an axial slot, means for supporting said sound box selectively adjacent a set of strings of the piano, a radio receiving and sound producing device, and means for connecting said radio receiving and sound producing device with the sound box, said connecting means communicating with the interior of the sound box.

10. In a device of the character described, the combination of a tubular sound box having an opening in one side thereof, a radio receiving and sound producing device, a support opposite said opening integral with said sound box for the radio receiving and sound producing device, stems extending through said sound box opening, and means 115 on said stem for clamping the sound box to the strings of a piano.

In witness whereof I affix my signature.

OSCAR A. BERMAN.
